UNITED STATES PATENT OFFICE.

WILLIAM A. WATSON, OF MALDEN, MASSACHUSETTS.

NOTE-SHEET-CONTROLLING BRAKE.

1,280,598.

Specification of Letters Patent.

Patented Oct. 1, 1918.

Original application filed January 8, 1915, Serial No. 1,224. Divided and this application filed June 7, 1915.
Serial No. 32,547.

To all whom it may concern:

Be it known that I, WILLIAM A. WATSON, of Malden, in the county of Middlesex and State of Massachusetts, have invented certain new and useful Improvements in Note-Sheet-Controlling Brakes, of which the following is a specification, this application being a division of my application Serial #1224, filed January 8, 1915.

10 This invention relates to automatic musical instruments and especially to the mechanism for controlling the passage of a perforated note sheet over the tracker bar of a player piano.
15 In such instruments, during playing, the lower roll is driven and is called the take-up spool. As the convolutions of the note sheet increase, the diameter of this roll increases, the upper roll correspondingly decreasing
20 in diameter. These varying diameters cause a variation in the load, or the power required to do the work of causing the note sheet to travel. Moreover, the air pressure upon the sheet traveling over the tracker bar, due to
25 the suction in the tubes which lead from said bar, causes a constant variation in the friction resistance to the travel of the sheet. That is, this friction is greater when no perforations, or very few, are opposite the
30 tracker holes, than when a larger number are opposite. With a uniform tension or braking action on the upper or let-off roll, there is a tendency to cause an irregular travel of the note sheet during the latter part of the
35 piece, especially when the roll is a large one. This is because, when the take-up spool has many convolutions or coils of the sheet upon it, the decreasing diameter of the let-off or record roll, and the variation of the friction
40 above mentioned, retard or hold back the sheet until the take-up spool has tightened the coils sufficiently to overcome the resistance. These clips or momentary stops are so objectionable that dealers hesitate to furnish large rolls, especially to beginners.

The principal object of my invention is to provide an improved brake for the let-off or record spool, which will automatically lessen its action gradually, or commensurate
50 with the reduction of the diameter of the roll, in order to permit long note sheets to be played to the end without hesitation.

Another object is to provide improved

winding and re-winding mechanism to facilitate accurate playing.

55

With these and further objects in view, my invention consists in the improvements which I shall now proceed to describe and claim.

Of the accompanying drawings, in which similar reference characters designate similar parts of features:

Figure 1 is a front elevation of a preferred embodiment of my invention.

Fig. 2 is a partial plan view of the same.

Fig. 3 is an elevation from the right of Fig. 1, on a larger scale.

Figs. 4, 5 and 6 are detail elevations illustrating the brake elements in different positions of operation.

70

Fig. 7 represents a section on line 7—7 of Fig. 4.

The end walls 12, 13 of the tracker bar or spool box support the tracker bar 39, the take-up spool 15 and the record spool 16. 75 The latter is, of course, as usual, removable. When in place, and re-winding is being performed, it is driven by its chuck spindle 17. During playing, the transmission gearing is in such a shifted position that the spindle 80 17 is disconnected from the motor, but the spindle must still rotate with the spool 16 as the music sheet is drawn from it over the tracker bar, onto the take-up spool, owing to the chuck 18 fitting the usual slot recess 85 in one end of the spool. Any braking action, therefore, on the spindle 17, is transmitted to the spool 16.

Secured to the spindle 17 is a brake wheel 19 having a smooth periphery. Adjacent to the wheel 19, and mounted loosely on a sleeve of wheel 19, is a disk 20 having a pinion 21 fast therewith. To the disk, at substantially diametrically opposite points 22, 23, are pivotally connected two arms 24, 25, having weighted outer portions 26, 27, and inwardly extending portions 28, 29, near their pivots, shaped to constitute brake shoes to act on wheel 19 to retard unwinding from the record spool. The parts indicated at 22, 24, 26, 28 constitute a lever of the second order, and the parts indicated at 23, 25, 27, 29 constitute a lever of the first order. The object of this will appear presently.

The disk 20, being loose on the spindle although having some slight frictional con-

nection therewith due to its sleeve mounting, would be rotated off balance if there were but one weighted arm or braking lever. Hence, the employment of two, so mounted 5 on the disk as to counterbalance each other.

A stop pin 30 projecting from the fixed upright 13 into an arc slot 31 formed in the disk 20, coöperates with one end or the other of said slot to limit the movement of the 10 disk and its brake levers about the spindle 17, to the two extremes substantially represented by Figs. 5 and 6.

Meshing with the pinion 21 is a toothed member illustrated as a gear wheel 32 carried by a rock shaft 33 mounted in the uprights 12, 13, said shaft having a finger 34 to bear against the surface of the record roll. As the oscillations of the disk and pinion 20 are through but a portion of one rotation (about one-half), only a few of the teeth 15 of member 32 are ever utilized and therefore said member is practically or operatively a toothed segment and might be so constructed.

25 When the parts are assembled, the intermeshing of the toothed members or gearing 21, 32, is such that when the finger 34 is bearing against the record roll in the position shown in Fig. 2, the disk 20 holds the 30 pivoted arms or levers so that the weights cause the brake shoes to bear on the wheel 19 with substantially maximum pressure. During playing, the spindle 17 and wheel 19 are rotated in the direction of the arrow *a*, 35 Fig. 4, which represents about the position of the parts at the beginning of the playing of a rather large roll. It is at this time that the maximum braking action is required in order that the paper may be wound so 40 closely on the take-up spool that there will be no slipping of the coils thereon when the latter portion of the piece is being played. As the roll unwinds, the frictional mounting of the disk 20 on spindle 17 tends to rotate 45 the disk and the pinion 21 in the same direction, and to rotate the toothed member 32 and rock shaft 33 in a direction to cause the finger 34 to bear against the surface of the record roll and to follow the gradually 50 diminishing diameter thereof. Therefore, said finger has some braking or retarding action. At the same time the finger acts as a feeler or controller for the brake shoes. As the record roll becomes smaller, the finger 55 or feeler 34, through shaft 33 and the gearing members, permits the disk and the brake levers to slowly move or adjust themselves toward the position shown in Fig. 5. As they do so, that component of the force of 60 gravity which causes the brake shoes to press on the wheel 19 gradually lessens. The parts described are so proportioned relatively as to render this lessening of the braking action commensurate with the reduction of the 65 diameter of the record roll or spool.

Fig. 5 illustrates the position which the brake levers assume when or just before, the last of the piece is being played, at which time it is preferable that the brake shoes shall be out of contact with the wheel 19. 70 Said figure clearly illustrates why gravity causes the shoes to separate from the wheel.

It is, of course, desirable to limit the swing of the brake levers, especially to prevent the weight 27 from contacting with the wheel 19 when the parts are in the Fig. 5 position. To this end, the disk 20 is provided with a pin 35 which projects through a slot or hole 36 in arm 24, said hole being large enough to permit the arm to swing within the desired limits. The disk has another pin 37 projecting into hole 38 in arm 25 similar to the hole 36 of arm 24.

It is desirable that all braking action shall cease whenever the note-sheet is being rewound onto the record spool. The structure described causes this to be effected automatically at any point of playing; that is, whether the entire piece has been played, or it is desired to rewind for a short distance 80 to repeat some intermediate part. The instant that the transmission gear is shifted to rewind and the spindle 17 begins to rotate in the direction of the arrow *b* in Fig. 6, the disk 20 is moved in the same direction, there 85 being sufficient friction between it and the sleeve hub of wheel 19 to start the movement, since the brake levers counterbalance each other. Immediately after this start has been effected, the levers reach a position where 90 the shoes bear on wheel 19, the motion of which then causes the levers to quickly move to the position of Fig. 5, the shoes then 95 separating from the wheel. The disk moves until arrested by stop pin 30 in slot 31. At 100 the same time, the gearing members 21, 32, cause the finger brake or controller 34 to swing far enough back to be completely out of the way of any changing of record spools. When the disk reaches the position of Fig. 105 6, the weights 26, 27 occupy such positions that the brake shoes will be either slightly separated from the wheel 19 or will touch it so lightly as to have no appreciable braking action. As soon as playing begins again, 110 with the same roll or another one, the first movement of the spindle 17 in the direction of the arrow *a* in Fig. 4 causes the disk and 115 brakes to swing from the position of Fig. 6 back to the position of Fig. 4 until the 120 finger or controller 34 contacts with the surface of the roll, thus automatically returning the brake devices to proper position to effect the necessary retarding action 125 on the record roll to insure winding of the paper so closely upon the take-up spool that later there will be no slips or hesitation in the travel of the paper.

For the best results, it is desirable not only that the longitudinal movement of the 130

note sheet over the tracker bar shall be steady and under the full control of the motor, but also that its lateral position relatively to the suction holes in the tracker

5 bar shall be under control. I will now proceed to describe my improvements to provide for this last mentioned control, and also my improved structure of two-part tracker bar, one part being movable relatively to the other, one having the "speaking" or note holes which may be shifted for transposing or regulating, the other having the holes which control expression and may, therefore, be termed the mechanical 10 controlling holes.

The tracker bar comprises a fixed member 39 and a slidably adjustable member 40 having holes 41 for the usual purpose, to cooperate with note selecting holes or slots 20 of a note sheet 42. The member 39 is removably secured in fixed position relatively to the spool box by suitable means, such as by screws passing through the walls 12, 13 into the ends of said member, said member having a slot or recess 54 from which projects a finger 55 which, as described in my application 1224 above referred to, is preferably in the form of a lever one end of which constitutes or carries a valve to 30 co-act with the inner end of a tube 57. The tube 57 (see Fig. 1) communicates with the interior of a pneumatic 59, the fixed side of which is secured by suitable means such as stays 60 projecting rigidly from wall 12. 35 A tube 61 connects the interior of the pneumatic 59 with the suction mechanism of the instrument so as to have a constant tendency to collapse the pneumatic, the movable wall of which is connected by a light link 62 with 40 an arm 63 of a vertical rock shaft 64 (Figs. 1 and 2), the latter having short arms 65, 66, which overlap the projecting ends of the spindles of the record and take-up spools. These spools are normally held to 45 ward the right by springs 67 in their left-hand bearings, but during playing, the collapsed or partially collapsed pneumatic 59 exerts a pull on link 62 so that the short arms of the rock shaft hold the spools 50 shifted somewhat to the left, against the action of springs 67. If now the note sheet tends to travel out of proper position so that its left-hand edge acts on guide finger 55 to admit air through tube 57 and result 55 in the expansion of the pneumatic the springs 67 can shift the spools sufficiently to the right to restore the correctness of tracking.

As described more fully in my application 60 1224 of which this application is a division, the holes 41 of the member 40 of the tracker bar are connected by air tubes with valve mechanisms for controlling the hammers of the piano action, and by adjusting said member in the direction of its

length, the holes 41 may be so shifted relatively to the apertures in the note sheet as to effect transposition.

It is to be understood that during re-winding, which is rapid, the note sheet 70 leaves the finger 55 and is not worn or curled by contact therewith. This is because the pneumatic 59 is not collapsed during re-winding and consequently the spools are shifted by their bearing springs 67 sufficiently to remove the edge of the sheet from the finger, the latter remaining in its fixed location. As the power for collapsing the pneumatic 59 is derived from the pneumatic chest or stack, no especially designed 75 devices for cutting off the suction from the pneumatic 59 during re-winding are necessary. Such cutting off of the suction may be effected by the usual cutting out devices of the wind chest when re-winding. Therefore, it is unnecessary to illustrate or describe such devices herein.

Having now described my invention what I claim is:

1. In mechanism for supporting and actuating the note-sheet of an automatic musical instrument, a brake wheel rotatable with the record spool, a brake, means for supporting the brake to permit it to bear with more or less pressure on said wheel, 90 means for shifting said brake in the plane of rotation of the wheel, and means whereby the force of gravity will variably affect the braking action of the brake according to the position to which it is shifted in said plane.

2. In mechanism for supporting and actuating the note-sheet of an automatic musical instrument, a brake wheel rotatable with the record spool, a brake, means for supporting the brake to permit it to bear with more or less pressure on said wheel, means for shifting said brake in the plane of rotation of the wheel, whereby the force of gravity will variably affect the braking action of the brake according to the position to which it is shifted in said plane, and means controlled by the diameter of the record spool for fixing the position of said brake.

3. In mechanism of the character described, the combination with a record spool spindle having a brake wheel, of a brake for the periphery of said wheel, means for supporting the brake to permit it to swing 120 in the plane of rotation of the wheel, a feeler bearing against the record spool, and connections between the feeler and the brake whereby the position of the brake in said plane is positively varied according to the variation of the position of said feeler.

4. In mechanism of the character described the combination with a record spool and its spindle, the latter having a brake wheel, of a gravity friction brake for said 130

wheel coöperating with the periphery of said wheel, means for supporting the brake to permit it to swing in the plane of rotation of the wheel, and means for varying 5 the braking action of the brake to cause it to diminish as the diameter of the record spool decreases.

5. In mechanism of the character described, the combination with a record spool 10 spindle having a brake wheel, of a carrier rotatably mounted on said spindle, a brake connected with the carrier, means controlled by the diameter of the record spool for oscillating the carrier, and means whereby the 15 force of gravity will variably affect the braking action of the brake according to the position of said carrier.

6. In mechanism of the character described, the combination with a record spool 20 spindle having a brake wheel, of a carrier rotatably mounted on said spindle, a pair of counterbalancing gravity brake levers connected with the carrier, means controlled by the diameter of the record spool for oscillating the carrier and means whereby 25 the force of gravity will variably affect the braking action of the brake according to the position of said carrier.

7. In mechanism for supporting and actuating the note sheet of an automatic musical instrument, a brake wheel rotatable with 30 the record spool, a brake, means for supporting the brake to permit it to bear with more or less pressure on said wheel, means 35 for shifting said brake in the plane of rota-

tion of the wheel, whereby the force of gravity will variably affect the braking action of the brake according to the position to which it is shifted in said plane, and means controlled by the position of the brake for 40 rendering the brake ineffective during re-winding of the note sheet.

8. In mechanism for supporting and actuating the note sheet of an automatic musical instrument, a gravity brake acting on 45 the record spool spindle, a feeler bearing against the record spool, and connections between the feeler and brake to vary the braking action of the brake according to the position of the feeler, said connections including means to remove the feeler from the spool during re-winding.

9. In mechanism for supporting and actuating the note sheet of an automatic musical instrument, a brake wheel rotatable 55 with the record spool, a brake, means for supporting the brake to permit it to bear with more or less pressure on said wheel means for shifting said brake in the plane of rotation of the wheel, whereby the force 60 of gravity will variably affect the braking action of the brake according to the position to which it is shifted in said plane, and means controlled by the position of the brake for automatically rendering the brake 65 ineffective during re-winding and returning it to operation when playing is resumed.

In testimony whereof I have affixed my signature.

WILLIAM A. WATSON.
